The ornamental design for a pharmacy consulting booth, as shown and described.

DESCRIPTION

FIG. 1 is a perspective view of the pharmacy consulting booth, illustrating the pharmacist access to the pharmacy consulting booth.

FIG. 2 is a top perspective view of the pharmacy consulting booth, again illustrating the pharmacist access to the pharmacy consulting booth and from an opposite side of the pharmacy consulting booth to that presented in FIG. 1.

FIG. 3 is a perspective view of the pharmacy consulting booth, illustrating the customer/patient access to the pharmacy consulting booth.

FIG. 4 is a top perspective view of the pharmacy consulting booth, again illustrating the customer/patient access.

FIG. 5 is one end view of the pharmacy consulting booth at the pharmacist access.

FIG. 6 is the other end view of the pharmacy consulting booth at the customer/patient access.

FIG. 7 is one side view of the pharmacy consulting booth.

FIG. 8 is the other side view of the pharmacy consulting booth.

FIG. 9 is a top view of the pharmacy consulting booth; and, FIG. 10 is a bottom view of the pharmacy consulting booth. The broken lines in the accompanying drawings illustrate representative environmental structure in the form of a cabinet that forms no part of the claimed invention.
